STACKER

Ralph F. Barber, Elmhurst, Ill., assignor to Miller Wrapping & Sealing Machine Company, a corporation of Illinois

Filed Feb. 27, 1962, Ser. No. 175,915
10 Claims. (Cl. 271—79)

This invention relates to article stacking means and, more particularly, means for stacking limp film sheets such as bags or the like.

An object of this invention is to provide a new and improved stacking device.

Another object of this invention is to provide a stacking device for limp sheets, such as bags or the like, in which timing of the stacking means is not critical with respect to an adjacent machine which is feeding the sheets to be stacked.

A further object of the invention is to provide a stacking device in which the leading part of successive sheets are supported and fed out over a base or platform on which the sheets are stacked with the leading part of the sheet held impositively only by friction whereby the stacking means may continue on and the sheet is released without any positive control.

Other objects of the invention are to provide a stacking device as defined in the preceding paragraph having a plurality of supports for individually supporting the leading part of a sheet with a supply of the supports being maintained in a storage station awaiting use as required to handle any desired length of sheet and means are provided for releasing air between a sheet being placed on the stack and the top of the stack, including a transversely sloped platform or base and means are provided for holding the sheet stack in position as a successive sheet is drawn onto the stack.

Further objects and advantages will become apparent from the following detailed description taken in connection with the accompanying drawings in which:

FIGURE 1 is a fragmentary side elevational view of the stacking device with parts of the bag feeding machine shown broken away;

FIGURE 2 is a fragmentary end elevational view of the stacking device looking at the left-hand end of FIGURE 1;

FIGURE 3 is a diagrammatic view showing the operation of the stacking device;

FIGURE 4 is a vertical section on an enlarged scale taken along the center line of the stacking device toward the right-hand end thereof as viewed in FIGURE 1 and showing a plurality of bag supports in various positions provided in the machine;

FIGURE 5 is a plan view of the structure shown in FIGURE 4;

FIGURE 6 is a plan view of a single sheet support on an enlarged scale shown in association with the endless chain members providing movement thereof;

FIGURE 7 is an end view of the mechanism shown in FIGURE 6;

FIGURE 8 is a side elevational view of the mechanism shown in FIGURE 6;

FIGURE 9 is a detail view of the adjustment mechanism for controlling the cycling of the stacking device;

FIGURE 10 is a diagram of the circuit for obtaining operation of the stacking device; and

FIGURE 11 is a showing of a modified form of platform or base for the sheets.

While this invention is susceptible of embodiments in many different forms, there is shown in the drawings and will herein be described in detail an embodiment of the invention together with a modification thereof with the

2

understanding that the present disclosure is to be considered as an exemplification of the principles of the invention and is not intended to limit the invention to the embodiment illustrated. The scope of the invention will be pointed out in the appended claims.

The stacking device as disclosed herein is suitable for stacking bags made of limp film which comprise two sheets of material secured along their edges except for an open end and which issue from the bag-making machine in flat form. The device is capable of use with a bag-making machine, such as shown in Weist Patent No. 2,882,956, with a part of such machine being shown in FIGURE 1. A motor 10 drives a shaft 11 and a clutch 12 with the shaft 11 having a belt drive connection 13 to one roller of a pair of feed rollers 14 and 15 which advance the formed bag past a pair of cutters 16 and 17 with the cutter 17 being movable to cut off the bag. As disclosed in the Weist patent, the clutch 12 includes a switch-operating member 18 for controlling the length of bag that is made.

The stacking device is indicated generally at 20 and comprises a stand 21 suitably constructed to engage the floor and includes a pair of side supports 22 and 23 mounting the platform or base of the stacking device for movement between the normal operative position shown in full line in FIGURE 1 and an out-of-the-way position shown in broken line in FIGURE 1.

The platform for the stack of sheets is indicated at 24 and comprises a generally rectangular plate extending for the length and width of the stacking device, which is supported from a pair of side plates 25 and 26 which extend downwardly in spaced parallel relation with the side supports 22 and 23 of the stand. The plates 25 and 26 are connected by a tube 27 which has pins 28 and 29 at its ends whereby the platform can be pivoted between the positions shown in FIGURE 1.

The stacking device includes continuously driven endless chains which run along each side of the stacking device with one chain being indicated at 30 and the other at 31 in FIGURE 2. The chain 30 passes about a sprocket 32 at one end of the stacking device and a sprocket 33 at the opposite end which is located at a loading station adjacent the discharge end of the bag-making machine. The chain 31 passes about a corresponding pair of sprockets 34 and 35. As shown in FIGURE 3, this results in the chains having a lower reach which is driven in a direction travelling away from the loading station and at a level spaced above the level of the platform 24 and an upper reach for return of the supports to a storage station at an upper level to be subsequently described.

The drive for the chains is derived from a motor 36 having a variable speed pulley thereon which drives a belt 37 passing about a pulley 38. The pulley 38 is on a shaft with a sprocket driving a chain 39 which engages with a sprocket 40 on a shaft 41 which carries the aforementioned sprockets 32 and 34. The speed of the drive can be varied by manipulation of the hand wheel 42 to vary the distance between the split pulley and the pulley 38, as well known in the art.

At this point reference may be made to FIGURE 3 which shows the operation diagrammatically. A sheet or bag is shown in full line issuing from the feed rolls 14 and 15 of the bag-making machine to the loading station for the stacking device, in which the leading part of the sheet extends forwardly. A subsequent position of the bag is shown in broken line in which the leading part of the bag is frictionally wrapped about a support member which carries it out across the platform for dropping onto the bag stack supported on the platform 24. Three different bag supports are shown in FIGURE 3 with each of the

supports comprising a pair of rods or bars 45 and 46. The bars waiting at the loading station are identified as 45a and 46a, the bars in an operating cycle are identified as 45b and 46b and a pair of bars at a station awaiting advance to the loading station are identified as 45c and 46c.

The bars of each support are arranged for selective drive engagement with the chains 30 and 31 travelling along the sides of the platform.

Reference may now be made to FIGURES 4, 6 and 7, for a more detailed description of one of the supports for the leading part of a sheet or bag. The pair of bars 45 and 46 extend between a mounting bracket 47 at one of their ends and another mounting bracket 48 at the opposite ends thereof. The bar 45 is rotatably mounted in the bracket 47 and has a tubular part 49 and a chain engaging sprocket 50 secured thereto for rotation therewith, while the other end of the bar is rotatably mounted in the bracket 48 and has a chain engaging sprocket 51 secured thereto for rotation with the bar.

Each bag support has brake means associated therewith for determining whether the sprockets 50 and 51 may freely rotate as driven by the chains or whether the sprockets will be held against rotation relative to the brackets 47 and 48. This brake device comprises a generally U-shaped brake arm 52 pivoted at 53 to the bracket 47 and carrying a curved steel brake member 54 which may engage against the tubular part 49 rotatably affixed to the support bar 45. The brake device also includes a first detent 55 engageable at locations and times described hereinafter to release the brake and a second detent 56 functioning similarly to the detent 55 when engaged as described subsequently. The brake arm 52 is normally urged to an on position by a spring 57 engaged between the brake arm and the bracket 47.

Trailing parts of the brackets 47 and 48 mount the support bar 46. In order to hold the bag support on the chains an upper part of the brackets 47 and 48 mount shoes 60 and 61 which slide against the upper parts of the chains when the chains are moving relative thereto and which travel with the chains at other times. Similar shoes 62 engage both above and below the chains at the rear of the brackets 47 and 48.

The sets of bars of the bag supports in FIGURE 4 have been identified similarly to those in FIGURE 3 to show various positions of the supports with a pair of additional bag supports shown in a storage station.

At the loading station, a support is held in position to receive a leading part 63 of a bag by engagement of the leading detent 55 of a support by a latch 66 to throw off the brake member 54. This latch is carried on an arm 67 pivoted at 68 on the frame and operated through a link 69 by a solenoid 70. When the solenoid 70 is actuated, the latch 66 is pivoted in a clockwise direction, as viewed in FIGURE 4, to release the detent 55 of the brake device with the result that the brake member 54 can engage the tubular part 49 to hold the sprockets against rotation relative to the chains 30 and 31 and the support is carried along with the chains to move through a bag or sheet stacking cycle. This condition is shown in FIGURE 4 with the support having bars 45b and 46b in which the leading part 63 of the sheet has wrapped about the bar 45b. It will be noted by comparison of these two positions that the angular disposition of the bars 45 and 46 has also changed. When the bars are at the loading station, they are in vertically spaced relation with one above the other to permit easy entry of the leading part 63 of a bag therebetween and when the support bars move onto the lower reach of the chain, the bars are in horizontal spaced relation to facilitate a good frictional engagement with the leading part of a bag.

The support having bars 45c and 46c is held at a position immediately preceding the loading station by a latch 71 which engages the trailing detent 56 of the brake arm to release the brake and permit rotation of the sprockets 50 and 51 without resultant movement of the support,

with the support also actually being held by the latch 71. The latch 71 is mounted for upward releasing movement on a lever 72 pivoted to a frame support at 73 and is pulled upwardly by a solenoid 74. When the latch 71 is pulled upwardly, another latch 75, mounted on the lever 72, is moved downwardly to engage and hold a succeeding support until such time as the latch 71 moves down into position to hold a support. When this occurs, the latch 75 moves up to permit advance of a support to the latch 71.

An added supply of bag supports can be stored immediately preceding the latches 71 and 75 as provided by an idler belt 76 overlying the trailing detents 56 of the bag supports for engagement therewith to throw off the brakes 54. The belt 76 is an idler and is mounted on a frame 77 for vertical movement, with the frame being supported on a pair of links 78 and 79 which are pivoted on a frame member 80. When a support is to move to the latch 71, a solenoid 81 is actuated to raise the frame 77 and the belt 76 to again permit the brakes 54 to be set to cause advance of the supports until the leading support is engaged by the latch 75 and then by the latch 71. A bar 82 extends through this area to be engaged by a roller 83 on the bracket 47 for support of the bracket.

The circuit for operation of the solenoids 70, 74 and 81 referred to is shown in FIGURE 10 in which the circuit to the solenoid 70 for release of the latch 66 is operated from a switch 85 operated from the control of the bag-making machine and which is arranged to operate a short time interval after the bag-making machine has started to feed a bag beyond the cutting knives 16 and 17 by operation of the feed rolls 14 and 15. The solenoid 74 for release of the latch 71 is operated by a switch 86 operated by the movable knife 17 on the bag-making machine to send a support to the loading station after a preceding bag has been cut off by the bag-making machine. The solenoid 81 is operated by a switch 87 which is positioned to be engaged by the lever 72 during the actuation and release of the latch 71 so as to raise the idler belt 76 and permit advance of bag supports to the position of the latch 71.

The actuating member 18 shown in FIGURES 1 and 9 corresponds to the member 35 of the Weist patent for determining the end of the feeding movement of the bag-making machine by engagement with a switch as described in the patent, with the return of this member to a zero position of engagement with a plate 90 secured to a shaft 91. An operator 92 for the switch 85 controlling the latch release solenoid 70 is also movable with the switch operating member 18 and the position of the switch 85 is variable under the control of a hand operated worm 93 driving a gear 94 on the shaft 91. The switch 85 is carried on a collar 95 loose on the shaft 91 whereby it is rotatably positioned from rotation of the worm 93 through a gear 96 fixed to the shaft meshing with a gear 97 on a shaft 98 carrying a gear 99 meshing with a gear 100 fixed to the sleeve 95. The gears 96 and 100 are of slightly different size so as to provide a different ratio of adjustment between the switch 85 and the zero plate 90 to obtain variable timing of actuation of a support for the leading part of a bag with respect to the total length of bag being fed to the stacking device. In this way, it is made certain that the leading part of a bag will be supported until the bag is fully placed on top of the stack before the support bars 45 and 46 leave the leading part of the bag and travel onto the upper reach of the chains. The adjustment referred to is maintained by friction retarding springs 101.

It will be seen from the foregoing structure that a construction is provided in which the timing of operation is not critical due to the impositive frictional engagement of a leading part of a bag with the bars 45 and 46 of a support. A leading part of the bag will be fed between these bars and the bars will then commence to move to carry the leading part of the bag forwardly over the stack

as the bag is still being fed from the bag-making machine. Once the bag is cut off by the knives 16 and 17, the bag will settle onto the stack and the leading part of the bag will slide out of and away from engagement with the bars 45 and 46 to the left of the position shown for bars 45b and 46b in FIGURE 3. Because of the storage provided for a number of supports, it is possible to properly feed out bags of any length, since one, two, three or more bag supports can be moving about the total path of movement at the same time, with one support leaving the leading edge of a bag, while the next support is receiving another bag, and a further support can be still travelling to the storage location at idler belt 76.

In order to hold the stack in place as a bag is being fed thereonto, a pair of pads may be provided one at each side of the platform with one of these being shown in FIGURE 1. The pad includes a gripper 105 carried on an arm 106 pivoted at 107 with actuation from an air cylinder 108 whereby as a sheet is approximately lined up with the stack the cylinder 108 is operated to raise the gripper which deflects the edge part of the bag until the gripper is on top of the sheet and the gripper then descends upon release of air to the cylinder 108 to descend onto the top of the stack. The pivot 107 is a shaft extending to the other side of the machine where a similar gripper 105 is located adjacent the edge of the platform. This upward movement of the grippers 105 also aids in expelling air from under the individual bag so that it will better move into place on the stack.

An alternate embodiment of the platform 24 is shown in FIGURE 11 in which the platform is raised along its center with the sides thereof sloped as indicated at 24a and 24b and with the platform actually being defined by a pair of conveyor belts 110 and 111 which can be suitably driven in a manner known in the art to, at the desired interval, be energized to move a stack from the platform. With the highest part of the platform along the longitudinal center line thereof, a bag will settle upon the stack with the center part thereof first engaging the stack and the bag settling progressively toward the edges to gradually expel air from beneath the bag.

I claim:

1. A device for stacking relatively limp lengths of material comprising, a platform on which the material is stacked, a pair of endless members traveling one at each side of the platform, and a pair of bars extending transversely of the platform and mounted at their ends to the members, said bars being in fixed spaced apart relation to have the leading part of a length of material threaded therebetween whereby said material is frictionally held by the bars for movement therewith.

2. A bag stacker for stacking bags issuing from bag making machinery having bag advancing means for advancing a bag at a first rate of speed comprising, a stacking platform, and means for frictionally carrying the leading part of a bag to a point to have the bag disposed at a stacking location above the platform including a member traveling along the platform on which the leading part of the bag is supported for movement therewith and relative thereto, and means for advancing said member at a rate of speed greater than said first rate to have the member leave the bag at said stacking location.

3. A bag stacker as defined in claim 2 including a movable member for holding a stack of bags in place.

4. A stacking device for sheets of limp material comprising, a base on which the sheets are stacked, a pair of continuously driven endless members traveling one at each side of the base with a lower reach traveling away from a loading station and an upper return each, a support for

- the leading part of a sheet comprising a pair of bars in fixed spaced apart relation extending transversely of the base and operatively connected to the members for selective movement with the members, means for holding the support at the loading station with the bars located generally one above the other for movement of a leading part of a sheet therebetween, and means releasing the support for travel along the lower reach with one bar trailing the other to obtain good frictional engagement with the sheet.
5. A stacking device as claimed in claim 4 in which a plurality of supports are releasably associated with said endless members, and means for storing all but one of said supports at a location awaiting successive advance to said loading station.
10. 6. A device for stacking sheets of material comprising, a base having an end disposed adjacent a machine from which the sheets are fed, a pair of continuously driven endless chains located one at each side of said base and passing around sprockets at ends of the base to define upper and lower chain reaches, a support for a sheet comprising a bar extending transversely of the base, mounting means at each end of the bar comprising a bracket rotatably mounting the bar, a sprocket attached to the bar and in engagement with the chain, and brake means movably mounted on the bracket for selective engagement with the bar whereby engagement of the bar prevents rotation of the bar and sprocket to cause the bar to travel with the chains and release of the brake permits rotation of the sprocket so that the chain can move relative thereto.
15. 7. A device as defined in claim 6 in which the brake means is yieldably urged to an engaging position, including means selectively engageable with the brake means at an end of the base to hold the brake released until a sheet is received by the bar.
20. 8. A device as defined in claim 7 including other means selectively engageable with the brake means at a bar storage station to hold the brake released until a bar is required at said end of the base.
25. 9. A device as defined in claim 8 in which the sheet support comprises a second bar in spaced parallel relation with the aforementioned bar.
30. 10. A device for stacking sheets of material comprising, a base having an end disposed adjacent a machine from which the sheets are fed, a pair of continuously driven endless members located one at each side of said base and having upper and lower reaches, a support for a sheet comprising a bar extending transversely of the base, mounting means at each end of the bar comprising a bracket rotatably mounting the bar, a rotatable member attached to the bar and in engagement with one of the endless members, and brake means movably mounted on the bracket for selective engagement with the bar whereby engagement of the bar prevents rotation of the bar and rotatable member to cause the bar to travel with the endless members and release of the brake permits rotation of the rotatable member so that the endless member can move relative thereto.
